LOCK

Application filed April 8, 1926. Serial No. 100,702.

This invention relates to locks and particularly to locks for sliding closures, such as cages in banks.

Primarily the invention comprehends a lock which is designed to be gravitationally locked and electrically released although the same is intended to broadly cover mechanical releasing means.

More specifically, the invention contemplates a lock between the closure and closure frame in which an apertured bolt is carried by one of said members and in which a lock casing constituting a keeper is carried by the other of said members, said lock casing having an opening receiving the bolt, a locking element gravitationally projectable through the bolt aperture and means normally holding the gravitational locking element inactive and engageable by the bolt when projected into the lock casing for releasing the locking element to permit of its gravitational movement to a locking relation with the bolt aperture.

The invention aims as a still further object to provide a lock of the character set forth which is comparatively simple in construction, inexpensive to manufacture, and which is thoroughly reliable and highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a sectional view of the lock casing illustrating the bolt released;

Fig. 2 is a similar view illustrating the bolt in locked relation;

Fig. 3 is a detail plan view of the bolt.

Referring to the drawings by characters of reference, A designates a portion of a sliding door or closure and B the doorway or closure frame.

The lock constituting the invention includes a bolt 10 having a base 11, which is attached to the door or closure A, and which bolt is provided with a vertical aperture 12. A lock casing 13 is secured to the doorway or closure frame B and its front wall 14 is formed with a bolt-receiving opening 15. A horizontal partition 16 is arranged within the casing 13 between the upper wall 17 and the lower wall 18, said partition being substantially in alignment with the upper edge of the bolt-receiving opening 15. A vertically movable locking element 19 is designed to normally descend by gravity, through the partition 16, so that its lower end is received in a socket or recess 20 formed in the lower wall 18 of the lock casing. In order to maintain the locking element 19 in a raised position, a support 21 is provided to normally underlie the lower end of the locking element, said support being maintained in position by a spring 22 which surrounds the support stem 23 and is interposed between a spring seat 24 on the support stem and one of the pair of arms 25 of a bracket 26 which is attached to the under side of the partition 16. The spring forces the spring seat into engagement with the opposite arm 25 of the bracket so that the support 21 is limited to a normal position underlying the locking element 19.

In practice, the locking element 19 will preferably be in the nature of the core of a solenoid 27, which solenoid when energized will effect a vertical lifting movement of the locking element 19 to release the bolt 10 when locked by the locking element and permit of the opening of the closure A. It is of course to be understood that within the scope of the invention the locking element 19 may be mechanically lifted in any desired manner.

In operation, when the closure A is moved to a closed position, the bolt 10 is projected through the bolt-receiving opening 15 where the free end of the bolt encounters the support 21 and moving the same against the action of the spring 22, causes the support element to release the locking element 19, allowing the same to gravitationally drop.

through the bolt opening 12 where its lower end is received in the socket 20. This effectually locks the closure in its closed condition until the locking element is lifted. If 5 the locking element is the core of a solenoid, as illustrated, when the solenoid is energized the core or locking element 19 is raised so that when the closure A is opened and the bolt is removed from the casing, the spring 10 22 will simultaneously effect the shifting of the support 21 to a normal retaining position underlying the locking element or core 19.

As illustrated, the support element 21 is 15 preferably formed of an inverted L-shaped piece so that the horizontal arm 28 thereof, which is of a length substantially equal to the distance between the free end of the bolt 10 and the bolt opening 12, will serve to 20 maintain the locking element 19 in a raised position until the bolt opening 12 substantially underlies or intersects the path of movement of the locking element thereby preventing friction and wear between the 25 lower end of the locking element and the upper face of the bolt 10. It is of course understood that the vertical depending arm 29 of the support is engaged by the nose or free end of the locking bolt when the 30 closure is moved to a closed position.

The invention is especially designed as a lock for cages in banking institutions so that the tellers and clerks will be provided with a convenient means for locking and releasing the closures of the cages, it being 35 obvious that the movement of the cage closure to a closed position will automatically effect its locking.

What is claimed is:

40 1. A lock comprising a bolt having a vertical opening, a casing having an opening in its front face to receive the bolt and provided with a horizontal apertured partition and a socket in its lower wall, a gravity 45 locking member mounted above the partition and having an unbroken peripheral surface, said members being adapted to extend through the aperture thereof and pass through the opening in the bolt into said 50 socket when the bolt is projected into the casing, an inverted U-shaped bracket on the under side of said partition, an inverted L-shaped support having a stem projecting from its vertical member and slidable in 55 the bracket, a spring surrounding the stem between the members of the bracket and normally holding the horizontal member of the support below the opening of the partition with the end of the locking member resting 60 thereon, the vertical member of the support being adapted to be engaged by the bolt and slide it inwardly and thereby release the locking member.

65 2. A lock including a casing having an apertured horizontal partition, a bolt-receiving

ing opening below the partition and a socket in its lower wall, a bolt projectable into the casing and having a vertical aperture, a solenoid vertically mounted in the casing above the partition, a core in said solenoid with its lower end in the aperture of the partition and substantially flush with the lower face of the partition, said core constituting a locking element gravitationally engaging the bolt aperture and the socket of the casing when the solenoid is de-energized, and a sliding and spring-pressed support mounted on the under side of the partition and upon which the core normally rests to maintain it in elevated position, said support being slidable from under the aperture of the partition by the bolt whereby to permit of the gravitational locking engagement of said core with the bolt aperture and the casing socket when the solenoid is de-energized.
